UNITED STATES PATENT OFFICE

2,046,230

VENDING MACHINE

Alfred Paul Wolff, Stockton, Calif.

Application January 7, 1935, Serial No. 755

1 Claim. (Cl. 312—84)

This invention relates to vending machines and more particularly that type of vending machine adapted to dispense slender articles.

The primary object of this invention resides in the provision of a vending machine adapted to contain a quantity of different brands of cigarettes or the like for selective delivery at the will of a purchaser.

Another object of this invention resides in the provision of a vending machine consisting of a plurality of cigarette chutes in communication with delivery cylinders actuated independently of one another by a purchaser desiring to procure the contents of a particular chute.

A still further object of this invention resides in the provision of a vending machine consisting of a plurality of cigarette chutes communicating with delivery cylinders controlled in sets by means coacting with a handle common to each set of cylinders.

In addition to the aforesaid objects, this invention resides in the provision of a vending machine for slender articles, such as cigarettes, cigars and the like, consisting of article containing chutes in communication with delivery cylinders preferably disposed in sets and having common actuating means governed by coin controlling means.

Aside from the foregoing objects, this invention resides in the provision of a vending machine consisting of a plurality of article chutes communicating with sets of delivery cylinders actuated by means common to each set of cylinders and cooperating with coin controlled means associated with coin ejecting means.

Among the salient features of this invention is the provision of a selective delivery mechanism adapted to dispense a predetermined number of articles (one in this instance) upon disposing a coin in association with ejecting means therefor.

With these and other objects in view, this invention resides in certain novel features of construction and arrangement of elements to be hereinafter fully set forth in the specification, illustrated in the accompanying drawings and pointed out in the appended claim and, while the disclosure depicts my present conception of this invention, the right is reserved to make such changes in construction as come within the scope of the claim.

In the accompanying drawings forming a part of this application:

Fig. 1 is a front view of a vending machine as constructed in accordance with this invention.

Fig. 2 is a plan view thereof.

Fig. 3 is a vertical sectional view approximately on line 3—3 of Fig. 1.

Fig. 4 is a horizontal sectional view approximately on line 4—4 of Fig. 1.

Fig. 5 is a vertical sectional view approximately on line 5—5 of Fig. 2.

Fig. 6 is a detail sectional view on line 6—6 of Fig. 4.

Fig. 7 is a similar view on line 7—7 of Fig. 4.

Fig. 8 is a similar view on line 8—8 of Fig. 4.

Fig. 9 is a similar view on line 9—9 of Fig. 4.

Fig. 10 is a detail sectional view on line 10—10 of Fig. 4.

Fig. 11 is a detail perspective view of a portion of one of the coin plungers.

In the present embodiment of this invention the numeral 5 designates, in general, a vending machine adapted to dispense slender articles such as cigarettes, cigars and the like and, while this application discloses the machine as adapted to dispense the aforesaid articles, its utility may be extended to dispensing package or other articles by substituting appropriate chutes and delivery cylinders of similar construction.

This machine is preferably constructed to provide a casing 6 having an inclined chute 7 and delivery tray 8.

Secured within the casing 6 are article retaining chutes 9 which are preferably closed at their upper ends by a cover 10 secured to the casing 30 by suitable locking means 11.

In the present instance the chutes 9 are arranged in sets, herein indicated by the letters A and B and are associated, at their lower ends, with sets of delivery cylinders C and D, each set 35 of which is loosely journaled on a shaft 12 mounted in bearing blocks 13 and extending to the exterior of the casing where handles or knobs 14 are provided to rotate the shafts. The aforesaid delivery cylinders are provided with suitably formed pockets 15, one of which is adapted to register with the associate chute when the same is in neutral or non-operative position.

Secured to or otherwise formed on each delivery cylinder at its opposite ends are ratchet gears 45 16, each cylinder having the teeth of its ratchet gears disposed in opposite directions for engagement with dogs 17 pivotably mounted on a block 18 secured or otherwise formed on the shaft 12 and other dogs 19 pivotably secured to the bearing blocks 13.

Through the instrumentality of the shaft 12 and dogs 17 which engage oppositely disposed ratchet gears 16 one of the cylinders in each set is permitted to rotate in one direction while its 55

companion cylinder is held against rotation through coaction of its ratchet gear 16 and associated dog 19, whereupon opposite rotation of the shaft 12 causes the previously stated stationary cylinder to rotate therewith and the previously stated rotating cylinder to remain stationary through the engagement of its ratchet 16 and associated dog 19. This manipulation of the cylinders, for instance, set C permits selective delivery of articles from either of chutes A dependent upon the direction in which the shaft is rotated.

Secured to the shaft 12 in any suitable manner is a disk 20 having a series of grooves 21 in one of its surfaces, said grooves being approximately of the area of a coin and preferably equal in number to the pockets in the delivery cylinders.

Associated with the disk 20 and adapted to normally be seated in one of the grooves 21 is a pivoted locking block 22 which is held into engagement with the disk 20 by a spring 23 to not only lock the disk against rotation but to govern the rotation thereof by lodging in each groove as it aligns therewith, thus it will be observed that means are provided to simultaneously lock the disk 20 and associated rotating elements, together with controlling the delivery of the articles selected.

Extending from the aforesaid locking blocks 22 and disks 20 are coin chutes 24, the lower ends of which are open and in communication with the grooves 21 in the disk 20 so as to direct the coins beneath plungers 25, which are retained in spaced relation to the disk 20 by springs 26 and provided with knobs 27 above the casing in convenient access of a purchaser.

With this assemblage of elements, it is apparent that, upon dropping a coin into the selected chute, it will lodge in a recess K between the disk 20 and locking block 22, whereupon the associate plunger is manipulated to force the

coin between the disk 20 and locking block 22 so as to dislodge the locking block from the groove 21. Having completed this manipulation of the coin plunger, it is released and returned to its normal extended position by the spring 26, whereby the handle 14 and associated elements are freed for manipulation to procure a single selective article from one of the article retaining chutes.

Preferably beneath the disk 20 is a suitable coin receiving box X which is of the usual construction.

While this application discloses adjacent sets of chutes, delivery cylinders and their associated elements as set forth, a greater or lesser number of units can be assembled in a casing to meet the demands of the public.

With this invention fully set forth, it is apparent that means are provided whereby a multiplicity of articles of different brands can be stored for dispensing according to the demands of the purchaser and, through the simplicity of the embodiment, the machine can be manufactured and sold cheaply.

Having thus fully described my invention what I claim and desire to protect by Letters Patent is:

In a vending machine of the character set forth the combination, of sets of article retaining chutes, aligned delivery cylinders having pockets communicating with the chutes, ratchet gears on opposite ends of the cylinders, the teeth of the ratchet gears on each cylinder being oppositely disposed to those on the other cylinder, a shaft loosely passing through the cylinders, a block secured on the shaft between the cylinders, oppositely directed dogs on the block and engaging certain ratchet gears on the cylinders, bearing blocks supporting the shaft, and oppositely directed dogs on the bearing blocks and engaging certain other ratchet gears of the cylinders.

ALFRED PAUL WOLFF.
